US00D949034S

(12) **United States Design Patent** (10) **Patent No.:** **US D949,034 S**
(45) **Date of Patent:** **** Apr. 19, 2022**

(54) **BODY COMPOSITION METER**

(71) Applicant: **Tanita Corporation**, Tokyo (JP)

(72) Inventor: **Shigeharu Azuma**, Tokyo (JP)

(73) Assignee: **Tanita Corporation**, Tokyo (JP)

(**) Term: **15 Years**

(21) Appl. No.: **29/715,682**

(22) Filed: **Dec. 4, 2019**

(30) **Foreign Application Priority Data**

Jun. 7, 2019 (JP) 2019-012617

(51) **LOC (13) Cl.** **10-04**

(57) **CLAIM**

The ornamental design for a body composition meter, as shown and described.

DESCRIPTION

FIG. 1 is a perspective view of a body composition meter, showing the new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings depict portions of the body composition meter that form no part of the claimed design.

1 Claim, 7 Drawing Sheets
